UNITED STATES PATENT OFFICE

ARMAND CHABOT, OF ANDERLUES, BELGIUM

APPARATUS FOR CARBONIZING SOLID FUEL

Application filed November 20, 1928, Serial No. 320,657, and in Belgium July 19, 1928.

The present invention is relative to an apparatus for carbonizing coal or mixtures of coal and other solid fuel, intended to furnish finished products in blocks or pieces of determined size and shape.

For this purpose, the product to be treated is placed, according to the invention, in moulds or matrices having the shape and the size of the finished products to be obtained, 20 said moulds or matrices forming part of a movable chassis or slide adapted to be placed in an oven and whereby the finished products in blocks or parts of given size and shape can be obtained without having to employ 25 any binding substance and without any preparation whatever. The thus obtained products have no longer to be broken to size and give very little waste matter.

An oven for carbonizing coal or other fuels 20 can comprise a long tube in cast iron or other material, in which are effected the various stages of the combustion, i. e. drying, heating, distillation and carbonization.

According to the invention, this tube is 25 divided into two longitudinal compartments, preferably superposed the one upon the other, whereby a lower compartment is obtained through which can pass an endless conveyor carrying the fuel or product to be treated, and 30 an upper compartment adapted to collect the distillates coming from the lower compartment, said upper compartment being fitted with outlet pipes for this purpose. Said two longitudinal compartments of the tube 35 are separated by a device provided with apertures, slots or slits for the passage, from the lower into the upper compartment, of the volatile products produced in the lower compartment; this device provided with apertures, 40 slots or slits can be formed of a perforated plate, which can be stationary or movable, or of a number of movable transverse rollers, capable of being shifted by the coal mass 45 travelling in the lower compartment and being specially suited for coals which are liable to swell. The endless conveyor can be formed of a chain of scrapers composed of a number of segments forming the matrices or moulds 50 of the products to be obtained, said chain of

scrapers fitting exactly into the lower compartment of the tube.

According to the invention, the upper compartment of the tube can be fitted with baffles, 55 stoppers or the like, or can be constructed in such a manner as to form a number of transverse chambers, separated from each other by said baffles or the like, cooperating with the segments of the chain of scrapers, to form tight partitions between said chambers, 60 whereby a distillation in several stages can be effected and the water, gases and tars of varying qualities can be obtained.

The heating of the oven can be effected by 65 electricity or by the combustion of solid, liquid, gaseous or powdered fuel, and the hot gases will be directed into a channel or flue in contact with the tube, in such a manner as to heat consecutively the portion of the tube forming the carbonization chamber, the portion of the tube forming the distillation chamber and the portion of the tube forming the drying chamber.

According to the invention, the channel or 70 flue for heating the tube can be provided with baffles or partitions, or can be constructed in such a manner that the heating of the tube is effected on all sides for certain portions of said tube, and that said tube is only 75 heated along its lower side or its lower and one or two of its lateral sides for the other portions, whereby the cavities and recesses 80 in the mass are avoided.

According to the invention, the tightness 85 of the tube can be obtained by the segments of the endless conveyor or chain of scrapers, filled with fuel to be treated at the fore end of the oven and by the segments filled with finished products at the rear end of the oven, said segments travelling through parts 90 of the tube of smaller cross sectional area provided at the front and rear end of the tube.

According to the invention, the tube can 95 comprise a number of portions of smaller cross sectional area, such as the portions serving to secure the air-tightness of the tube, the portion separating the drying chamber from the distillation chamber and portions dividing 100 the distillation chamber itself into a

number of sub-chambers, whereby a distillation in several stages can be obtained.

The invention will be described hereafter, with reference to the accompanying drawing, which illustrates, merely by way of example, an embodiment of the invention.

Fig. 1 is a longitudinal section through the oven;

Fig. 2 is a horizontal section through the same;

Fig. 3 is a section through III—III of Fig. 1;

Fig. 4 is a section through IV—IV of Fig. 1;

Fig. 5 is a section of the tube through V—V of Fig. 1;

Fig. 6 is a section of the tube through V—V of Fig. 1, the tube being provided with rollers;

Fig. 7 is a part of the chain of scrapers.

With reference to the drawing, the oven comprises a tube *g*, which is divided longitudinally into two compartments by a perforated sheet metal plate *k* (Fig. 5) or by a series of rollers (Fig. 6). This perforated plate *k*, which can be stationary or movable, forms a lower compartment, in which can move the endless conveyor or conveyors, and one or more upper compartments, which receive the water vapour, gas and tar distilled from the lower compartment, which latter products are discharged by the pipes *j*, *j*₁.

The endless conveyor, which in the example illustrated on the drawing is formed of a chain of scrapers, but which could be formed, say of two chains, say of more chains of scrapers arranged side by side, or the one above the other, or in any other way, or which might be formed of one or more endless conveyors of different types, fits exactly in the lower compartment of the tube *g*. The chain of scrapers *f* is formed of segments *u* (Fig. 7), constructed in such a manner that they form the matrice or mould of the products to be obtained, which may be cubes, polyhedrons, briquettes, etc.

The upper compartment of the tube *g* is fitted with a number of baffles or stoppers *s*, and in certain places the area of this upper compartment can be reduced or completely suppressed to form parts *p*₁, *p*₂, *p*₃ of smaller cross sectional area, which baffles *s* and parts *p* cooperate with the segments *u* to form tight partitions dividing the tube along its length into a number of chambers. The tube *g* comprises consecutively, starting from the fore end of the oven: a feed chamber, consisting of a hopper *e* and a piston *i*, which presses the coal into the matrices or moulds of the chain *f*; a first part *p*₁ of smaller cross sectional area, intended to separate the feed chamber from the drying chamber *c*; said drying chamber *c*, which is fitted with outlet

pipes *j* taking off the steam produced in said chamber *c*; a second portion *p*₂, of smaller cross sectional area, intended to isolate the drying chamber *c* from the distillation chamber *b*; said distillation chamber *b*, which can itself be divided into a number of sub-chambers, by means of the baffles *s*, which cooperate with the segments of the chain of scrapers to form tight partitions, whereby a distillation in several stages can be effected and distillates of varying qualities can be obtained and taken off by the different outlet pipes *j*₁; a carbonization chamber *a*; a third part *p*₃ of smaller cross sectional area, forming the cooling chamber *d*, the cross sectional area of the tube of this part being such that the chain of scrapers fits exactly in the tube and forms an air-tight stopper. This latter arrangement of the tube *g* is also used for the portion located between the feed hopper and the drying chamber. The cooling of the products in the cooling chamber *d* can be effected by the air or by a water circulation. It must be understood that the number of baffles or stoppers *s*, fitted in the distillation chamber *b*, can vary to suit the circumstances and that they can be suppressed when a single continuous distillation chamber is required.

The oven can be heated by any means whatever: by electricity, by solid, liquid, gaseous or powdered fuel. The heating agent travels in the opposite direction of the chain of scrapers. In the embodiment illustrated, said heating agent is formed at the rear end of the oven and is evacuated at the front end by the chimney *n*, after it has passed, if required, through regenerators or other heat recovering apparatus. The fuel serving to heat the oven mingles with air in the pipes *m* and the hot gases are then directed into the burners *l*, from where they pass into the channel or flue *q*, which is preferably constructed in such a manner that the heating agent travels all round the tube *g* in the carbonization chamber *a*, so as to heat said tube on all sides (section IV—IV, Fig. 4), whilst the hot gases only travel along the bottom side or along the bottom side and one or two lateral sides of the tube *g*, in the distillation chamber *b* (section III—III, Fig. 3), so as to prevent recesses or cavities being formed inside the mass. The drying chamber *c* can also be advantageously heated on all sides.

The dimensions of each chamber will be calculated according to the nature of the material to be treated and the duration of the various operations will be determined by the quality of the product charged in the oven. The length of the various chambers will allow of calculating said duration.

No air must be allowed to penetrate inside the tube. For this purpose, the chain *f* can be completely enclosed in an air-tight casing; the finished products can then be discharged

into a double-entry hopper. The air-tightness can also be obtained by means of suitable packings. In the embodiment illustrated, this air-tightness is obtained at the front part of the oven by the segment of the chain of scrapers containing the coal, which segment forms air-tight piston, and at the rear end of the oven by the segment containing the finished products. If there are any interstices at the rear end of the apparatus, they can be stopped by adding a suitable product, such as sand or coke dust.

It is obvious that the shape of the combustion chamber will depend on the heating process employed. Similarly, the shape of the oven will vary according to circumstances; the oven may be of the single or of the multiple type, and in the latter case, the ovens can be arranged next to each other or can be superposed on each other. Each oven can comprise one or more chains, which can be disposed horizontally or vertically and the advancing speed of said chains will depend on the operation to be made in the oven. If, instead of carbonizing coal, any other material was to be heated, either in contact with the air or in vacuum, or in any fluid whatever, at a constant or variable temperature, the speed would have to be appropriated to the results to be obtained.

The oven is of a very simple construction and only requires a very low driving power. The supervision, hand-labour and upkeep are exceedingly small; all parts of the oven being easily accessible, the treatment can be followed from beginning to end. The oven does not present the slightest danger and its cost-price is very low.

The oven according to the invention allows of making in a continuous manner semi-coke in parts or blocks of determined size, without having to pass through a mechanical preparation, a mixture with binding substances or the various operations of crushing, which always give rise to various classes of coal and at the same time to great quantities of waste matter. In this oven, the separation of the products such as water, tar, gas, is made in air-tight spaces and these products can be discharged separately from one another, whereby the quality of the thus recovered products is very high.

Moreover, during distillation, the oven is heated along its bottom side only, or along its bottom and one or two of its lateral sides, whereby cavities in the coal mass are avoided.

The coke obtained is of suitable density and its value is thus very high.

The products distilled during coking can be obtained at all stages of the distillation, whereby their value is increased and great subsequent costs are avoided.

With this oven, mixtures of fine particles of bituminous coal with fine particles of non-bituminous coal or other coal or coke breeze,

or others can be used without having to employ a binding substance, and after the by-products have been recovered, pieces or blocks of smokeless fuel of determined size can be obtained from said fuels.

70

I claim:

1. Apparatus for heating coal to produce agglomerate pieces of given size and shape comprising an endless chain of matrices having the size and shape of the agglomerate pieces of fuel to be produced, means to compress the fuel into said matrices, an oven of rectangular cross section divided longitudinally into an upper compartment and a lower compartment having a height equal to that of the matrices, means to frictionally translate said matrices through said lower compartment, means for heating said oven on all sides in the first part of its length and means for heating other parts of said oven on its bottom and a portion of its sides only.

75

2. Apparatus for heating coal to produce agglomerate pieces of given size and shape comprising an endless chain of matrices having the size and shape of the agglomerate pieces of fuel to be produced, means to compress the fuel into said matrices, an oven of rectangular cross section divided longitudinally into an upper compartment and a lower compartment having a height equal to that of the matrices, means to frictionally translate said matrices through said lower compartment, means for heating a part of said oven on all sides, means for heating other parts of said oven on its bottom and a portion of its sides only, and means to collect the vapours distilled from the fuel into the upper compartment.

80

3. Apparatus for heating coal to produce agglomerate pieces of given size and shape comprising an endless chain of matrices having the size and shape of the agglomerate pieces of fuel to be produced, means to compress the fuel into said matrices, an oven of rectangular cross section divided longitudinally into an upper compartment and a lower compartment having a height equal to that of the matrices, a number of juxtaposed but narrowly spaced rotatable transverse rollers separating said upper and lower compartments, means to frictionally translate said matrices through said lower compartment, means for heating a part of said oven on all sides, means for heating other parts of said oven on its bottom and a portion of its sides only, and means to collect the vapours distilled from the fuel into the upper compartment.

85

4. Apparatus for heating coal to produce agglomerate pieces of given size and shape comprising an endless chain of matrices having the size and shape of the agglomerate pieces of fuel to be produced, means to compress the fuel into said matrices, an oven of

90

- rectangular cross section, a device longitudinally dividing said oven into a lower and an upper compartment along certain portions of its length, means to frictionally translate said matrices through said lower compartment, means for heating a part of said oven on all sides, means for heating other parts of said oven on its bottom and a portion of its sides only, transverse partitions in the upper compartment forming various chambers and means for separately collecting the vapours distilled into said various chambers of the upper compartment.
5. Apparatus for heating coal to produce agglomerate pieces of given size and shape comprising an endless chain of matrices having the size and shape of the agglomerate pieces of fuel to be produced, an oven of rectangular cross section divided longitudinally into an upper compartment and a lower compartment having a height equal to that of the matrices, the wall separating said upper and lower compartments having slots, means to frictionally translate said matrices through 10 said lower compartment, means to heat at temperatures increasing along the length of the oven the first portion having the lowest temperature and heated on all sides, a second portion heated on its bottom and part of 15 its sides only and a third portion heated on all sides, and means to collect the vapours distilled from the fuel into the upper compartment.
6. Apparatus for heating coal to produce agglomerate pieces of given size and shape comprising an endless chain of matrices having the size and shape of the agglomerate pieces of fuel to be produced, means for moving said endless chain, a feed hopper, a piston adapted to reciprocate in said hopper and to compress the fuel into said matrices, an oven of rectangular cross section, a device longitudinally dividing said oven into a lower and an upper compartment, the cross sectional area of the lower compartment being equal to that of the endless chain, means to frictionally translate the endless chain through said lower compartment, means to heat parts of the oven on all sides and other parts on the bottom and on portions of the sides only, and means to collect the vapours distilled into the upper compartment.
7. Apparatus for heating coal to produce agglomerate pieces of given size and shape comprising an endless chain of matrices having the size and shape of the agglomerate pieces of fuel to be produced, means for moving said chain, a feed hopper, a piston adapted to reciprocate in said hopper and to compress the fuel into said matrices, an oven of rectangular cross section, said oven having parts of smaller cross sectional area at both ends and intermediate its ends, the end parts being such as to exactly embrace the endless chain and thus form fluid-tight packings with the matrices filled with fuel, a device longitudinally dividing said oven into a lower and an upper compartment, the cross sectional area of the lower compartment being equal to that of the endless chain, means to frictionally translate the endless chain through said lower compartment, means to heat parts of the oven on all sides and other parts on the bottom and on portions of the sides only, and means to collect the vapours distilled into the upper compartment.
8. Apparatus comprising an endless conveyor formed with matrices having the size and shape of the agglomerate pieces of fuel to be produced, a feed hopper, a piston adapted to reciprocate in said hopper and to compress the fuel into the matrices, an oven of rectangular cross section having parts of smaller cross sectional area at both ends and intermediate its ends, the end parts being such as to exactly embrace the endless conveyor and thus form fluid-tight packings with the matrices filled with fuel, a device longitudinally dividing said oven into a lower and an upper compartment, the cross sectional area of the lower compartment being equal to that of the endless conveyor, means to frictionally translate the endless conveyor through said lower compartment, means to heat parts of the oven on all sides and other parts on the bottom and on portions of the sides only, and means to collect the vapours distilled into the upper compartment.
- In testimony whereof I signed hereunto my name.
- ARMAND CHABOT.
